Specification for Design.

Patented May 20, 1919.

Application filed May 4, 1918. Serial No. 232,644. Term of patent 14 years.

To all whom it may concern:

Be it known that we, CECIL R. HUBBARD, a subject of the King of Great Britain, residing at Baden, Beaver county, Pennsylvania, and HOMER G. KNODERER, a citizen of the United States, residing at Edgeworth, county of Allegheny, and State of Pennsylvania, have invented a new, original, and ornamental Design for a Bushing-Base for Fittings for Electrical-Conductor Conduits, of which the following is a specification, reference being had to the accompanying drawing, forming a part thereof.

Figure 1 is a top plan view, Fig. 2 a side

elevation, Fig. 3 a bottom plan view, and Fig. 4 a right-hand end view of the bushing base for fittings for electric conductor conduits.

We claim:

The ornamental design for a bushing base for fittings for electrical conductor conduits, as shown.

CECIL R. HUBBARD.
HOMER G. KNODERER.
